COMBINED ASH TRAY AND EMESIS BASIN

William S. Horn, Jr., Fort Worth, Tex.

Application May 24, 1954, Serial No. 30,620

Term of patent 7 years

(Cl. D85—2)

FIG. 1.

FIG. 2.

FIG. 3.

To all whom it may concern:

Be it known that I, William S. Horn, Jr., a citizen of the United States, residing at Fort Worth, in the county of Tarrant and State of Texas, have invented a new, original, and ornamental Design for a Combined Ash Tray and Emesis Basin, of which the following is a specification, reference being had to the accompanying drawing, forming a part thereof.

Figure 1 is a top plan view of a combined ash tray and emesis basin, showing my new design;

Figure 2 is a front elevational view thereof; and
Figure 3 is a side elevational view thereof.

I claim:

The ornamental design for a combined ash tray and emesis basin, substantially as shown.
